NEWTON ELKIN, OF PHILADELPHIA, PENNSYLVANIA

SHOE AND METHOD OF MANUFACTURING SAME

Application filed August 19, 1930. Serial No. 476,270.

This invention relates to improvements in the manufacture of shoes, and more particularly to improvements in the construction of the lining at the heel portion.

3 A general object of the invention is to provide a novel heel lining which may be readily and economically constructed, and which will give maximum foot comfort and minimize slipping of the heel with respect to the 10 stocking of the wearer.

15 A more specific object is to provide a heel lining which is free from seams at the back; free from bulging seams at the sides, and which includes an insert of friction material but retains the normal appearance of the 20 leather lining at the top edge of the shoe.

Other objects of the invention will in part be obvious and will in part appear herein-after.

25 The invention accordingly comprises the several steps and the relation and order of one or more of such steps with respect to each of the others, and the article possessing the features and the relation of elements, 30 which are exemplified in the following detailed disclosure, and the scope of the application of which will be indicated in the claims.

For a fuller understanding of the nature 35 and objects of the invention, reference should be had to the following detailed description taken in connection with the accompanying drawings, in which:

Fig. 1 is a vertical longitudinal sectional view of the heel portion of a shoe, embodying the improved heel lining construction;

Fig. 2 is a horizontal sectional view taken along the line 2-2 of Fig. 1;

Fig. 3 is a plan view of Fig. 1 in perspective, looking downwardly and rearwardly; and,

Fig. 4 is a view similar to Fig. 3, illustrating another embodiment of the invention.

Referring more particularly to Figs. 1-3 of 45 the drawings, wherein one embodiment of the novel heel lined structure is illustrated, it will be seen that the shoe 10 is provided with a wooden heel 11, an upper 12, an inner sole 13, a sock lining 14, and a leather lining 15 on the inside of the upper 12, to which it

is secured at the top by one or more rows of stitching 16.

In the embodiment shown, the leather lining 15 is cut away from the bottom upwardly and rearwardly from a point 17 adjacent the front of the heel seat on each side to a point 18 within a small distance, as, for example, about $\frac{3}{8}$ inch from the top, at which point the cut-away section is severed from the main section of lining 15 along a straight line 55 from said point 18 to the upper edge of the lining, said straight line cut terminating short of the center point of the rear of the heel. The two ends of the lining 15 are then joined at 18 by a strap 19 of the same material and of the same width, which passes around the rear of the heel and is also secured to the upper 12 by a continuation of the stitching 16. The lower edges of the lining 15, 60 from said point 18 to the upper edge of the lining, said straight line cut terminating short of the center point of the rear of the heel. The two ends of the lining 15 are then joined at 18 by a strap 19 of the same material and of the same width, which passes around the rear of the heel and is also secured to the upper 12 by a continuation of the stitching 16. The lower edges of the lining 15, 65 where it is cut away, and of the strap 19 are bevelled on the inside, as indicated at 20 of Fig. 2. A friction piece 21, of somewhat larger area than that portion of the lining which has been cut away, is correspondingly bevelled at its upper edge, as indicated at 22, and is inserted with its bevelled edge behind the bevelled edge 20 of the member 15 and the strap 19, whereupon the corresponding bevelled edges are suitably secured together as by means of a double row of stitching 23 to 70 form a smooth non-bulging joint.

The friction piece 21, which covers the entire contact portion of the heel, may be formed of velvet or other suitable fabric, or of suede, leather or the like. Velvet is preferred because of its peculiarly efficient action and its neat appearance and long wearing qualities.

In the embodiment shown in Fig. 4, the 85 strap 19 is omitted and one end 15a of the lining is not terminated as aforesaid, but is brought around to one of the points designated as 18a, and is there attached to the other end of the lining 15; otherwise the construction is similar to that previously described.

It will thus be seen that by means of the present invention there has been provided a heel lining of a novel and useful construction, 90 of usual appearance from the outside of the 95

shoe, which will give maximum foot comfort and non-slipping qualities, and since certain changes may be made in carrying out the above method without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a shoe, a heel lining including, in combination, a two-part leather lining cut away at its bottom portion at the rear end upwardly toward but not to its upper edge, means for joining the resultant lining strips which leaves the center of the heel smooth and free from seams, said lining being bevelled outwardly at its cut away edge, a friction piece inserted at the cut away portion and having its edges correspondingly bevelled and secured to and behind said bevelled edge of said lining.

2. In a shoe, a heel lining including, in combination, a leather lining cut away at its bottom portion at the rear end upwardly toward but not to its upper edge and terminating short of the center point of the rear of the heel, said lining being bevelled outwardly at its cut away edge, a strap member secured to and joining the ends of said lining and having its lower edge similarly bevelled, and a friction piece inserted at the cut away portion and having its edges correspondingly bevelled and secured to and behind said bevelled edge of said lining and said strap, whereby the heel lining is free from vertical seams at the center point of the back.

3. In a shoe, a heel lining including, in combination, a leather lining cut away at its bottom portion at the rear end upwardly toward but not to its upper edge, one of the sides of the lining terminating short of the center point of the rear of the heel, and the other being elongated to extend around the rear of the heel and being joined to said first mentioned portion, said lining being bevelled outwardly at its cut away edge, a friction piece inserted at the cut away portion and having its edges correspondingly bevelled and secured to and behind said bevelled edge of said lining, whereby the heel lining is free from vertical seams at the center point of the back.

4. A method of constructing shoes including, in combination, the preparation of a composite lining for the heel portion by cutting away a two-part main lining at its bottom

edge on both sides, upwardly and rearwardly from the heel seat, joining the resultant main lining strips by seaming which is disposed laterally of the center of the heel, beveling the cut away edges outwardly on the outside, correspondingly beveling the upper edge of a friction insert on the inside, and securing the corresponding bevelled edges of the lining and insert together to form a smooth lining free from bulges at the joint. 75

5. A method of constructing shoes including, in combination, the preparation of a composite lining for the heel portion by cutting away the main lining at its bottom edge on both sides, upwardly and rearwardly from the heel seat but not to its upper edge, terminating each short of the center point of the rear of the heel, beveling said cut away edges outwardly on the outside, similarly beveling a strap member on its lower edge, joining the ends of said strap member to the ends of said lining, correspondingly beveling the upper edge of a friction insert on the inside, and securing the corresponding bevelled edges of the main lining, strap and insert together to form a smooth lining free from bulges at the joint. 80

6. A method of constructing shoes including, in combination, the preparation of a composite lining for the heel portion by cutting away the main lining at its bottom edge on both sides, upwardly and rearwardly from the heel seat but not to its upper edge, terminating one of the sides of the lining short of the center point of the rear of the heel 100 and forming the other with an elongated portion to extend around the rear of the heel, beveling the cut away edges and the lower side of the elongated portion outwardly on the outside, joining the elongated portion 105 to said first mentioned portion, correspondingly beveling the upper edge of a friction insert on the inside, and securing the corresponding bevelled edges of the main lining and the insert together to form a smooth 110 lining free from bulges at the joint. 115

7. In a shoe, a heel lining including, in combination, a two-part leather lining cut away at its bottom portion at the rear end upwardly toward but not to its upper edge, a friction piece of velvet inserted at the cut away portion covering substantially the entire contact area of the heel, means for joining the resultant lining strips which leaves the center of the heel smooth, said lining being bevelled outwardly at its cut-away edge and said friction piece being correspondingly bevelled and secured behind said bevelled edge of said lining to form a smooth heel lining free from bulges at the joint. 125

In testimony whereof I affix my signature.
NEWTON ELKIN.
